UNITED STATES PATENT OFFICE.

HERMAN C. BLANK, OF CHICAGO, ILLINOIS.

CARPET-NAILING STRIP AND GROUND CONSTRUCTION.

Application filed March 3, 1926. Serial No. 92,064.

My invention relates to building construction wherein a carpet nailing strip is attached on the floor adjacent the wall for convenience in attaching a carpet of any suitable style stretched upon the floor of the room.

Formerly it has been the practice to lay wooden blocks in brick, concrete or hollow tile walls or partitions, adjacent the floor line, to which the grounds were attached by nailing, and the base attached to the grounds by nailing or screws as desired. In the usual construction, these wooden blocks extend into outside walls, and entirely through partition walls, permitting grounds to be nailed into them from opposite sides of the partition walls.

Formerly, it has been customary to attach the carpet nailing strip to the concrete floor, by boring holes in the concrete floor beneath the carpet nailing strip, and driving nails or screws into wooden, or expansion plugs inserted in said holes.

One of the objects of my said invention, is to provide means for attaching the grounds to the wall, without inserting wooden blocks in the wall, as formerly.

Another object, is to provide means for attaching the carpet nailing strip in place without boring holes in the concrete or other floor.

A further object is to provide such a construction, which shall be more fire proof than the former method, in the fact that the wooden blocks extending through the walls are eliminated, thereby removing this means for fire to communicate from one room to another, as formerly.

With the above, and other objects in view, which will more particularly appear from the following specification, I have shown and described herein one embodiment of my invention in which grounds are attached to the walls, and carpet nailing strips are attached adjacent the wall as shown. From the illustration and description, it will be apparent that my construction lends itself to a variety of uses, in addition to the one embodiment shown, and which are readily adaptable from the style of construction herein shown.

In the accompanying illustration, in which like numerals or reference refer to the same part throughout the various views,

Figure 1, is a view of my anchor 6, as blanked out of a piece of flat metal.

Figure 2, is a side elevation of the anchor 6, showing the side portions folded back upon the main body.

Figure 3, is a top view of the anchor 6, as shown in Fig. 2.

Figure 4, is broken section of a partition wall constructed of brick, hollow tile or the like, showing my anchor, with ground, base, carpet nailing strip in place.

Figure 5 is a detail view of the staple 7 employed to attach the carpet nailing strip to the anchor.

Figure 6 is a section view showing an anchor with bends near the edges, and the edges turned outward.

In Fig. 4 I have shown a usual style of fire-proof construction, in which a partition of brick, hollow tile or the like are laid upon the floor to form a partition between the rooms of a building. To the wall it is customary to attach one or more grounds as 9, and to this ground is attached by nails or screws, as desired, the base 8. On the floor adjacent the wall is laid the carpet nailing strip 10, and this must also be attached either to the floor or wall.

In my new style of construction, I employ the anchor 6 as shown, which is laid on end between the layers of brick or tile, and held in position by the mortar between such brick or tile. To this anchor I have attached a single ground, as 9, by driving nails through said ground, and into the space between the two layers of the anchor. As the bricks, and mortar hold the two layers of the anchor in close contact, the nail wedges itself in between the layers, and is held firmly against removal or displacement. To provide an even stronger hold upon said nails, I have given the anchor a bend at 5, which not only tends to hold the anchor more securely between the bricks than a flat anchor would be held, but also when the end of the nail passes the said bend 5, it is bent slightly at the end, and tends to clinch said nail even more securely between the layers of said anchor, and even more firmly than it would be held in the wood blocks ordinarily employed in such construction.

In forming the anchor 6, as shown in Figs. 1, 2 and 3, I have employed a blank of the approximate shape shown in Fig. 1 with slits along the lines 3, 3. This blank I have bent with the end members 2, 2 bent back upon the body part 1, as shown at Fig. 3, forming two ears on each edge, one

at the top and one at the bottom. These ears 4, 4, 4, 4, are formed to a tubular shape, and adapted to receive and retain one end of the staple 7, as hereinafter described.

5 To attach the carpet nailing strip 10 I employ the staple 7, as shown in Fig. 5, one end of which is driven into the tubular ear 4 in the anchor adjacent said carpet nailing strip, and the other end is driven 10 into the said carpet nailing strip, as shown in Fig. 4. To complete the finish, the base as 8 is attached at the upper side to the ground 9 either by nails or screws, as desired, and the lower edge is attached to the 15 carpet nailing strip by driving nails through the lower edge of said base into the carpet nailing strip beneath, in toenail fashion. In addition, a quarter-round, as 11 is usually attached by nails driven into the carpet 20 nailing strip thus holding the lower edge of the base securely in place, without the requirement of the lower ground ordinarily employed where there is no carpet nailing strip into which nails may be driven to 25 attach said base.

As the anchors 6 extend entirely through the wall, and present the same opportunity of attaching ground, carpet nailing strip, and base upon each side of the partition 30 wall, as shown, it will be seen that the anchor provides a double purpose, and after the ground is attached upon each side, and the carpet nailing strip is attached to said anchor, the parts on either side tend to lock 35 said anchor against movement in the opposite direction, and each portion of the ground and base holds against the ground and base on the opposite side of the wall.

40 While it will be seen that the foregoing described construction omits the lower ground ordinarily employed in fastening the base, and is more economical, in that it saves one-half of the cost of grounds thereby, a lower ground may be attached just 45 above the ears 4, 4 at the lower edge of the anchor, and nails may be driven in between the layers of the anchor 6 to securely hold such lower ground, if it is desired, in the same manner as above described for attaching 50 the upper ground 9.

While I prefer to construct my said anchor with a curvature or bend at 5 therein, as shown, yet said anchor might be made with bends near the edges as in Fig. 6, or corrugated, or may be made without such curve or bend, and would hold fairly well, where the strain was not too great thereon, and will come within the general plan and intent of my said invention. Furthermore, 60 I have shown my said anchor 6 constructed with four ears 4, 4, 4, 4, and as the construction merely shows the use of the two at the lower edge, it will be apparent, that 65 two of these may be omitted in construction, if preferred, as they are only included

in my preferred construction for convenience in handling, as the style I have shown can be laid either end up, equally well, whereas, if it were constructed with ears 4, 4, at only one edge, it would be necessary 70 to always place said anchors in the wall with the ends having the ears downward.

By eliminating the wood blocks formerly employed in the wall to which to attach the grounds, I have saved a considerable expense, and by employing an anchor made of fireproof material, as metal, I have eliminated a means of the ready communication of fire through said wall from one room to the next in so-called fire-proof construction, 80 and substituted a construction which is not only fire-proof in theory, but in fact and is greatly appreciated in fireproof construction.

While I have only illustrated my device 85 as applied in a partition wall, it will be apparent that it may be equally employed in outside walls, or in walls where there is base and carpet nailing strip upon but one side of said wall, or if it were desired, said 90 anchor could be made with the ears for holding the carpet nailing strip upon but one side, without departing from the spirit of my said invention.

In the illustrations and foregoing descriptions I have shown how my device is adapted to a usual type of fire-proof construction. My said device is readily adaptable to the various forms of construction, and by merely varying the size, width, 100 height or other dimension, can be easily adapted to the various other forms of construction where it may be required.

Having thus described my said invention, what I claim and desire to secure by Letters Patent, is the following:

1. A device of the class described consisting of a sheet of metal folded back upon itself to form two substantially parallel members, tubularly formed ears at the upper and lower edges, and an opening between each respective pair of ears as shown and described.

2. A device of the class described consisting of a sheet of metal folded back upon itself to form two substantially parallel members, a bend formed near its middle portion, an opening partway of each edge having out-turned lips, and tubularly shaped ears at upper and lower edges adjacent said openings.

3. An anchor for building construction consisting of a sheet of metal doubled upon itself to form two substantially parallel members, with an opening at the edge and an ear formed at one portion of said opening, and a staple adapted to be attached in said ear.

4. In combination with a brick wall, an anchor for insertion in said wall, consist-

ing of a sheet of metal doubled back upon itself to form two substantially parallel members, said anchor having an opening and a tubular ear at the edge, grounds attached to the wall by means inserted between the members of said anchor, and a carpet nailing strip attached to said anchor by means of a staple having one point driven into said ear and the other point driven into said carpet nailing strip.

5. In building construction, the combination with a wall of a metallic anchor consisting of a sheet of metal doubled upon itself to form two substantially parallel members, with an opening at the edge, and

means inserted between said members for holding grounds attached to said wall.

6. In building construction the combination with a wall, of a metallic anchor consisting of a sheet of metal doubled upon itself to form two substantially parallel members inserted in said wall, having tubular ears at their edges, and means inserted in said ears for attaching carpet nailing strips, substantially as shown and described.
